CARRYING CASE FOR CIRCULAR SAW BLADES OR THE LIKE

Robert A. Bailey, 2339 E. 12th St.,
Des Moines, Iowa 50316

Filed Dec. 16, 1974, Ser. No. 533,456

Term of patent 14 years

Int. Cl. D3—99

U.S. Cl. D87—1 R

Fig. 1

Fig. 2

Fig. 4

Fig. 3

Fig. 5

Fig. 6

FIG. 1 is a front perspective view of a carrying case for circular saw blades or the like showing my new design;

FIG. 2 is a top plan view;

FIG. 3 is a side elevational view, the opposite side being a mirror image of the side shown;

FIG. 4 is an elevational view looking from the left of FIG. 3;

FIG. 5 is an elevational view look from the right side of FIG. 3; and

FIG. 6 is a bottom plan view thereof.

I claim:

The ornamental design for a carrying case for circular saw blades or the like, substantially as shown and described.
